UNITED STATES PATENT OFFICE.

JAMES MURPHY, OF TERRYVILLE, CONNECTICUT, ASSIGNOR TO THE EAGLE LOCK COMPANY, OF SAME PLACE.

PADLOCK.

SPECIFICATION forming part of Letters Patent No. 605,740, dated June 14, 1898.

Application filed December 23, 1897. Serial No. 663,139. (No model.)

To all whom it may concern:

Be it known that I, JAMES MURPHY, of Terryville, in the county of Litchfield and State of Connecticut, have invented a new Improvement 5 in Padlocks; and I do hereby declare the following, when taken in connection with the accompanying drawings and the letters of reference marked thereon, to be a full, clear, and exact description of the same, and which 10 said drawings constitute part of this specification, and represent, in—

Figure 1, a face view of a padlock embodying my invention; Fig. 2, a side view of the same; Fig. 3, a face view of the lock in its 15 closed position with the cap removed; Fig. 4, a similar view with the parts in their open position; Fig. 5, a sectional view on line *a b* of Fig. 3; Fig. 6, a plan view of the key; Fig. 7, a modification.

20 This invention relates to an improvement in padlocks of that class which are self-locking, the object being to produce a simple lock in which both ends of the shackle are locked when the shackle is in its closed position; and 25 it consists in the construction as hereinafter described, and particularly recited in the claims.

The case of the lock consists of a body *A* and cap *B*, which may be of any desired shape, 30 here represented as circular. The body and cap are connected together by rivets or posts *a b c d*, more or less in number. Upon the post *b* the shackle *C* is pivoted, and the shackle is constructed at its pivot end with 35 an inwardly-extending locking-lug *D* and at its opposite end or nose with a locking-notch *E*. Within the case and turning upon the key-hub *F* is a locking-guard *G*, formed at one side with an arm *H*, which is raised for 40 engagement with the locking-lug *D* of the shackle, and at the opposite sides with an arm *I*, which is also raised to pass over a tumbler *J*, which is mounted on the post *a*. In the arm *I* is a stud *K*, which passes into an inclined slot *L* in the said tumbler and so that 45 as the locking-guard is turned the tumbler will be moved from left to right. The upper end of this tumbler is formed with an upturned flange *M*, which passes into the notch *E* in the end of the shackle when the shackle 50 is in its closed position. Secured to the arm

H of the locking-guard is a spring *N*, which extends beneath the flange *M* and into the path of the nose of the shackle and so that when the shackle is released the spring will 55 tend to throw the nose of the shackle out of the case.

In opening the lock the key bears against the lower edge of the arm *I* and lifts the same, which forces the stud *K* upward, thereby moving the flange *M* at the upper end of the tumbler out of engagement with the notch *E* of the shackle. At the same time the rotation of the locking-guard releases the locking-lug at the pivot end of the shackle and so that 65 the shackle is free to be thrown open under the action of the spring *N*, and the said locking-lug passing over the upper edge of the arm *H* of the locking-guard prevents the return of the tumbler. As the shackle is turned 70 in closing, the locking-lug passes beyond the end of the arm *H* of the locking-guard, which is raised under pressure of the spring *N*, which is forced downward by the nose of the shackle. When the locking-guard is released by the 75 locking-lug, the notch *E* is in position to receive the locking-flange *M* of the tumbler, which is moved into it by the combined action of the slot and stud.

It is apparent without further illustration 80 or description that the stud *K* might be mounted in the tumbler *J*, and a slot formed in the arm *I*, and so that the tumbler would be operated in the same way as above described, or the stud might be formed in the 85 extreme end of the arm, so as to engage with the outer edge of the tumbler *J*, which would be so formed as to cause the tumbler to be moved inward as the arm is raised and as shown in Fig. 7. I therefore do not wish to 90 be understood as limiting the invention to the exact form of parts shown. A spring-lock in which the shackle is held at opposite ends is thus produced with a very small number of parts and at a correspondingly low cost 95 for manufacture.

Having fully described my invention, what I claim as new, and desire to secure by Letters Patent, is—

1. In a padlock, the combination with the 100 case, of a shackle pivoted therein, said shackle provided at its pivot end with a locking-lug

- and at its nose with a locking-notch, a tumbler also pivoted in the said case and adapted to engage with the nose of the shackle, and a locking-guard pivotally mounted in the case and adapted to be turned by the key and formed with two oppositely-extending arms, one of which is engaged by the locking-lug of the shackle and the other coupled with said tumbler for moving it, substantially as described.
2. In a padlock, the combination with the case, of a shackle pivoted therein, said shackle provided at its pivot end with a locking-lug and at its nose with a locking-notch, a tumbler also pivoted in said case and adapted to engage with the nose of the shackle, and a locking-guard pivotally mounted on the key-hub and so as to be turned by the key and formed with two oppositely-extending arms, one of which is engaged by the locking-lug of the shackle and the other end projecting over said tumbler with which it is coupled, substantially as described.

3. In a padlock the combination with the case thereof, of a shackle pivoted in the case and provided at its pivot end with a locking-lug and at its nose with a locking-notch, of a tumbler also pivoted in said case, and formed with a flange at its upper end for engagement with the locking-notch in the shackle, and with an inclined slot, a locking-guard also mounted in the case for movement by the key, said guard formed at opposite sides with arms one of which is adapted to engage with the locking-lug and the other provided with a stud to engage the inclined slot in the tumbler, and a spring, the tendency of which is to hold the locking-guard in its normal position, substantially as described.

In testimony whereof I have signed this specification in the presence of two subscribing witnesses.

JAMES MURPHY.
